DESK LAMP

Fumihiko Abe, Tokyo-to, Japan, assignor to Tada Kiko
Kabushiki Kaisha, Tokyo-to, Japan, a joint-stock company of Japan

Filed Apr. 20, 1966, Ser. No. 1,940

Claims priority, application Japan Jan. 18, 1966

Term of patent 3½ years

(Cl. D48—20)

FIG. 2

FIG. 6

FIG. 1 is a side elevational view of a desk lamp embodying my new design,

FIG. 2 is a front elevational view thereof,

FIG. 3 is a rear elevational view thereof,

FIG. 4 is a side elevational view thereof as seen from the left,

FIG. 5 is a top plan view thereof, and

FIG. 6 is a bottom view thereof.

I claim:

The ornamental design for a desk lamp, substantially as shown and described.
